G. C. Burton & Co. of the same place.

Letters Patent No 2080-Dated June 6-1865.

Design for a Cooking Stove.

The schedule referred to in these letters Patent and making part of the same.

For all whom it may concern:

Be it known that I, James G. Clarke, of Cincinnati, in the County of Hamilton and State of Ohio, have invented a new design for a Cooking Stove; and I declare that the same is fully and correctly represented in the accompanying perspective view thereof, which is hereby made a part of this specification.

What I claim as new and desire to secure by Letters Patent is:

The design for a cooking stove herein represented and described.

In testimony of which invention, I have set my hand.

Witnesses:
